UNITED STATES PATENT OFFICE.

MILO S. BURR, OF BOSTON, MASSACHUSETTS, ASSIGNOR TO HIMSELF AND THOMAS P. SMITH, OF SAME PLACE.

DESIGN FOR NURSING-BOTTLE.

Specification forming part of Design No. 6,270, dated November 26, 1872.

To all whom it may concern:

Be it known that I, MILO S. BURR, of Boston, in the county of Suffolk and State of Massachusetts, have invented or produced a new and original Design for a Nursing-Bottle; and do hereby declare the same to be fully described in the following specification and represented in the accompanying drawing, in which—

Figure 1 denotes a front, and Fig. 2 a side elevation of a nursing-bottle embodying my design or invention.

The nature of the said design is fully shown in the said drawing, to which reference is made.

In such drawing, A denotes the bottle, which

is made of glass and of any desirable size or capacity, and provided with a neck, a, and mouth b. On one side of the larger or base portion d of the bottle I form or imprint the representation of the bottle provided with its stopper, flexible tube, mouth-guard, and nipple, all combined and ready for use.

Having described my invention, what I claim is—

A nursing-bottle having the representation of said bottle with its adjuncts blown or formed in the side of the glass, as represented.

MILO S. BURR.
